UNITED STATES PATENT OFFICE

LEROY E. WILLIAMS, OF EDGERTON, WISCONSIN, ASSIGNOR TO HIGHWAY TRAILER COMPANY, OF EDGERTON, WISCONSIN, A CORPORATION OF WISCONSIN

LOCK FOR TILTING BODIES

Application filed January 2, 1929. Serial No. 329,867.

This invention relates to load-carrying vehicles of the type having a body mounted for rocking or tilting laterally for discharging its load, and has for its object to provide an improved form of locking and control means for securely holding the body in upright position or permitting prompt release for discharging its load. It consists of certain features and elements of construction in combination, as herein shown and described and as indicated by the claims.

In the drawings:

Figure 1 is an end elevation of a vehicle equipped with the locking and control means embodying the present invention.

Figure 2 is a side elevation.

Figure 3 is a fragmentary plan view of the control linkage.

The vehicle chosen for purpose of illustration includes an upwardly open hopper body, 10, carried on rockers, 11, mounted for rolling movement on transverse cross rails, 12, which are supported on the drop frame, 13, carried by the supporting wheels, 14. By virtue of this construction the body is adapted to be rolled or tilted laterally toward either side for discharging its load. Extending upwardly at each end of the vehicle frame, adjacent the ends of the body, is an A-frame, 15, which may be a cast member or as herein shown fabricated of structural plate, 16, and angle members, 17. Secured to the upper end of each A-frame is a cast member, 18, having an undercut head, 19, providing two oppositely and obliquely disposed abutment faces, 20, adapted to be engaged by a pair of latch members, 21, at each end of the body. These latches are positioned so that their contacting surfaces lie parallel to the abutting faces, 20, of the undercut head. The end of each latch is beveled at 22, to permit automatic locking of the body to the frame when it approaches upright position, as will hereinafter be described.

The latch members are each guidingly supported in brackets, 24, secured to the body; a coil spring, 25, being interposed in each bracket surrounding the latch for normally urging the same downwardly into locking position. Each latch has its upper end pivotal-

ly connected to one arm of a bell crank, 26, pivoted to the end of the body. The other arm of the bell cranks are pivoted to tie rods, 27, which are pivotally connected at their opposite ends to one arm of the bell cranks, 28, which are supported in brackets, 29, adjacent the corner of the body. Pivotally connected to the other arms of said bell cranks are longitudinally extending control rods, 30, disposed closely adjacent the sides of the body. These rods, 30, extend in pairs from opposite ends of the body, and each pair have their adjacent ends pivotally connected adjacent the middle of said body to an operating lever, 31, at opposite sides of its pivotal support, 32, so that in moving the lever to the left (with respect to the showing in Figure 2) the control rods, 30, through the other linkage will cause retraction or release of the corresponding latches at each end of the body to permit the body to be rolled to dumping position.

It will be seen that the locking mechanism is arranged so that when either set of corresponding latches on the ends of the body are retracted by their operating lever, the body is released for tilting only in the opposite direction, thus insuring the safety of the operator. Upon returning movement of the body it will be seen that as it approaches upright position the bevel faces, 22, of the latches contact against the undercut head, 19, yieldingly forcing the latches upwardly, permitting them to ride over the head, and when beyond the head the coil springs, 25, force the latches downwardly to engage against the sloping abutment faces, 20, of the heads. The inclination of the butting faces and latches is such that the body is firmly and positively held against vertical movement on the frame, such as might be incident to rebounding due to uneven roadway when the vehicle is in transit.

Desirably the ends of the tie rods, 27, adjacent the connection to the bell cranks are slotted as at 33, to provide a one-way connection between said rod and bell crank. Thus when the actuated latches are yieldingly urged upwardly as the body approaches upright position the motion is transmitted

through only a portion of the linkage and is absorbed in the one-way connection, thus obviating imparting the motion to all the linkage.

5 The body locking means embodying this invention permits dispensing with the side check chains ordinarily employed for stabilizing the body on the frame. Heretofore, to dump the body, the chains on the side opposite the direction of dumping, had to be released which required some time. The present invention provides a very convenient and simplified construction which insures stability of the body and prevents jumping or re-bounding of the body with respect to its frame when the vehicle is in transit.

10 My improved construction also reduces possible injury to the operator, as the control being located adjacent the center of the length of the body, permits the operator to be clear of hazardous positions. Locating the control lever centrally of the side of the body is also of advantage in that the operator may conveniently apply slight force to start 15 the body rolling to discharge its load. The locking mechanism is arranged so that the body can tilt only in the direction opposite to the side at which the operator is located; thus further guarding the safety of the operator.

20 I claim:

35 1. In combination with a vehicle frame and a body tiltably mounted thereon, an upright frame adjacent each end of the body, said upright frames each having an undercut head formed with two oppositely disposed stop faces, and a pair of spaced, longitudinally movable latches at each end of the body which engage said faces for locking 40 the body against lateral displacement with respect to said vehicle frame, said opposed faces of the undercut head being obliquely disposed and the latch members being mounted with their co-operating abutting 45 faces extending and movable in substantially parallel relation to the corresponding stop faces of the undercut head when the body is in locking position.

50 2. In combination with a vehicle frame and a body tiltably mounted thereon, an upright frame adjacent each end of the body, said upright frames each having an undercut head formed with two oppositely disposed stop faces, a pair of spaced latches 55 mounted for longitudinal movement at each end of the body and arranged for engaging said faces for locking the body against lateral displacement with respect to the vehicle frame, the engagement of the latches with 60 the undercut head serving also to prevent vertical displacement of the body, said latches having beveled faces extending obliquely with respect to their stop engaging faces, and yielding means normally urging 65 said latches in locking position, one of the

latches of each pair on the side opposite to the direction of tilting of the body being adapted for displacement by the cam action of their beveled faces against the undercut head as the body approaches its upright position.

70 3. In combination with a vehicle frame and a tilttable body thereon, an upright frame adjacent each end of the body, a fixed abutment on each of said upright frames, a pair of spaced latches on each end of the body for engaging opposing faces of said fixed abutments, yielding means normally urging said latches into locking position, means carried on each side of the body for controlling said latches, and means connecting each of said controlling means to a corresponding latch of each pair for releasing the body, the manipulation of either controlling means 75 permitting tilting of the body toward the opposite side, said yielding means normally returning the latches to operative position after the body is tilted, so as to automatically lock the body to the frame as the former approaches upright position, said connecting means including a one-way connection permitting said latches to automatically lock the body to the frame as the body approaches upright position, without imparting the motion back to the control means.

80 4. In combination with a vehicle frame and a tilttable body thereon, an upright frame adjacent each end of the body, a fixed abutment on each of said upright frames, a pair of spaced latches on each end of the body for 85 engaging opposing faces of said fixed abutments, yielding means normally urging said latches into locking position, means carried on each side of the body for controlling said latches, and means connecting each of said controlling means to a corresponding latch of each pair for releasing the body, the manipulation of either controlling means permitting tilting of the body toward the 90 opposite side, said yielding means normally returning the latches to operative position after the body is tilted, so as to automatically lock the body to the frame as the former approaches upright position, each of said 95 connecting means for operating the respective pairs of latches including linkage operatively connected to a bell crank pivotally mounted on the body, said connecting means including a one-way connection adjacent the bell crank.
